UNITED STATES PATENT OFFICE.

GEORGE EDGAR BRAGG, OF CINCINNATI, OHIO.

INTERNAL-COMBUSTION ROTARY MOTOR.

Application filed July 25, 1919, Serial No. 313,353. Renewed November 29, 1924.

My invention relates to a novel type of internal combustion rotary motor wherein the cylinders are mounted fast on a central shaft and are provided with pistons carrying at their outer ends rollers which contact with specially designed cam tracks so disposed and arranged as to utilize the thrust of the pistons against them to rotate the cylinders.

One object of my invention is to design the engine with a cylinder within which two opposing pistons work, which pistons are arranged to co-act with cam tracks so designed that I obtain in effect a three stroke cycle motor, since during each cycle the first stroke will carry both pistons on the power operation together, the second stroke will hold one piston while moving the other on the scavenging operation, and the third stroke will move the pistons together to effect the compression operation, thus completing the cycle. In other words, the pistons considered as a unit have performed the three foregoing separate and distinct operations during each cycle, notwithstanding the fact that each of the pistons individually completes only two strokes. In its preferred design the engine proper comprises two cylinders each offset from the engine center and arranged in parallelism, and each provided with its pair of co-acting pistons which complete the three stroke cycle operation above described.

A further object is to provide an automatic piston valve responsive in its action to the compression of air at the extreme outer stroke of the pistons of adjacent cylinders and movable thereby into position to bring the exhaust ports of the cylinder, previously in communication with the mixing chamber, into communication with the atmospheric exhaust for carrying off the gases.

A further feature of my invention is the manner of balancing the working pressure in all cylinders by having them in free communication at their inner ends and so controlling and timing the movement of their pistons as to cause a piston of each cylinder at the same time to stand at the outer end of its stroke holding exhaust ports open while the opposing two pistons are moving to scavenge the cylinders.

A further object of my invention is to provide all the cylinders with a common central explosion chamber into which the compressed air, driven into the mixing chamber

by the power stroke of the pistons, will be automatically discharged through pressure controlled valves as soon as the gases are exhausted from the cylinders and the pressure therein has dropped sufficiently to permit the compressed air in the mixing chamber to open the valves and enter the common explosion chamber.

A further object of my invention is to introduce both the sparking circuits and the fuel and lubricating oil pipes through the shaft and to by-pass the fuel oil into the mixing chambers, if it be of the lighter hydro-carbon series, but if of the heavier oils to deliver it into spray nozzles or injectors in the mixing chambers which are controlled by the piston valves so as to inject the oil spray after the scavenging operation in the combustion chamber.

A further object is to cause the highest pressure in the cylinders to be exerted through their piston rollers on the zones of maximum inclination in the cam tracks, thus most efficiently converting the piston energy into a rotary drive for the motor.

A further object of my invention is to arrange the rotating motor in a casing having ample air vents in its side walls so that the radiating fins with which the cylinders are provided will serve to air cool them.

It is within the contemplation of my invention that a series of such units may have their respective shafts coupled for joint operation, being properly set to bring their firing points at the proper relative angles about the shaft center in accordance with the number of units.

My invention further contemplates the use of two parallel cylinders, as a power unit, closed at their outer ends and each having opposing pistons working therein and controlling the intake, compression and exhaust of air in the outer ends of the cylinders in a radically novel manner. The air compressed by the piston's power stroke is forced past suitable valve means into a mixing chamber at each end of the motor and these chambers have inwardly opening air supply valves and outwardly opening valves for admitting air to the cylinders, which valves all respond automatically to the action of the pistons.

It is a further object of my invention to so design the curved tracks which are engaged by the piston rollers that they present zones of maximum inclination to the

rollers of pistons that are exerting their maximum power stroke and zones of relatively low inclination to the rollers of pistons during their compression strokes. By 5 this arrangement my motor attains the maximum efficiency in the conversion of radial and rotary movement from stator to rotor and accomplishes with the least possible angular strain the inward movement of the pistons to effect the requisite compression.

One of the most important objects of my invention is to produce a flexible low speed motor suitable for general purposes without 15 the sacrifice of power and compactness. To this end my motor is adapted, with the same piston displacement of the present motor types, to attain only twenty-five per cent of their maximum speeds for a given power 20 output, this being obtainable because the two opposite pistons in each cylinder will double the piston's travel during one stroke and my motor is designed to have two power strokes for every revolution, thereby enabling it to 25 produce four times as much piston travel in one revolution as would be obtainable in the present general type of motor. It follows therefore that it is capable of attaining maximum piston travel in one-fourth 30 as many revolutions and the minimum speed attainable is reduced proportionately. Moreover, by reason of the fact that my motor is designed to utilize the high cylinder pressure during the best working angle 35 of the stroke, or in other words maximum piston speed being at the beginning of the stroke, enables the piston to displace the rapid rise in pressure during combustion, whereas in the present type of motor the 40 minimum piston speed, which is comparatively very slow at the beginning of the piston stroke gradually increases as it approaches its best working angle, thus making it necessary for the motor to attain considerable speed before the piston is moving 45 fast enough to displace the rapid expansion of combustion so as to efficiently utilize the power thereof. The advantages of construction are obtainable without regard to which 50 of the co-acting general elements is regarded as the rotor and which the stator.

It is a further object of my invention to so design the curved tracks that the dead center positions of the pistons with reference thereto, are unequally spaced to the end that the piston shall be caused to complete its power stroke in the traverse of the shorter zones between dead center positions and to complete its return through the 60 longer zones. The shorter or power zones may represent an arc as small as 60° as compared with an arc of 120° for the exhaust and compression zones, this arrangement making it possible to cause the pistons to co-act with the track with maximum

efficiency and with maximum lineal travel in the cylinders, and hence maximum displacement, whereas the slow return provides ideal conditions for the exhaust, scavenging and compression operations.

My invention also comprises the various novel details of construction and arrangements of parts, which in their preferred embodiment only are illustrated in the accompanying drawings, in which:

Fig. 1 is a side elevation of a rotary engine embodying my invention.

Fig. 2 is a transverse sectional view taken on the line 2—2 of Fig. 3.

Fig. 3 is an enlarged transverse sectional view taken on the line 3—3 of Fig. 5, showing the rotor element only.

Fig. 4 is a sectional view enlarged of the motor taken on the line 4—4 of Fig. 3.

Fig. 5 is a partial sectional and partial plan view taken on the line 5—5 of Fig. 6.

Fig. 6 is a sectional view enlarged taken on the line 6—6 of Fig. 5.

Fig. 7 is an end view in detail of the rotating motor element.

Figs. 8, 9, 10, 11 and 12 are diagrammatic views showing the motor parts in different positions throughout the cycle of action.

Similar reference numerals refer to similar parts throughout the drawings.

In the embodiment of my invention illustrated I show the motor mounted in a circular casing comprising a peripheral wall 1 and flat side walls 2 which are bolted to the peripheral wall. This latter wall is cast integral with the base lugs 3 by which the casing is anchored to its foundation. Preferably also each side wall has cast integral therewith a cam track oblong in character and comprising diametrically opposite double track sections 4 curved inwardly from the periphery to the diametrically opposite points of maximum compression for the pistons as will be later described, and at that point the two tracks diverge, one forming opposite outwardly curving tracks 5, which are spaced further from the side wall than the other tracks which comprise opposite concentric sections 6 and outwardly curved sections 7, the sections 7 being similar in shape but advanced relatively to the outer track sections 5. It will be understood that each side wall 2 carries similar diametrically opposite track sections 4, 5, 6 and 7 which are symmetrically disposed.

The side walls 2 have suitably mounted therein axles 8 provided at their inner ends with flanges 9 (Fig. 4) which are bolted to the side spiders or webs 10 which are integral with or suitably connected to the cool outer ends of the cylinders 11 and 12 (Fig. 2) and stand clear of the radiating fins 13 surrounding the cylinders so as to permit a free circulation of air about them through

the large ventilating ports 14 provided in the casing's side walls. The center line of the axle passes midway between the centers of the cylinders which are closed at their outer 5 ends by a cylinder head 15 carrying a stuffing-box 16 through which its respective piston rod 17 passes. Preferably the adjacent heads are cast in pairs for rigidity of structure. Each piston rod is suitably connected 10 at its inner end to a piston 18 which reciprocates in one end of its respective cylinder, thus providing what for facility of description I may term four cylinders A, A', B, and B'. The cylinders A and B' are at adjacent 15 ends of the motor, leaving the cylinders A' and B at the other ends of the motor and between these pairs of cylinders is arranged a pressure equalizing combustion chamber 19 opening at its ends into the cylinders opposite 20 site the closure between the pistons at their extreme compression strokes. A spark plug 20 is disposed to operate in the combustion chamber 19 and adapted to ignite the entire compressed charge of gas between the four 25 pistons. Insulated sparking circuits 21 for the plug lead through one of the axles 8 while a fuel oil feed pipe 22 leads through the other axle and by a by-pass 23 enters the injectors 24 which have each a spray nozzle 30 projecting through the inner wall of the chamber 34 and adapted to spray the fuel into the combustion chamber 19. Each cylinder A, A', B and B' is provided near its outer end with a series of exhaust ports 26 35 and at its extreme outer end with an air port 27. The air ports 27 of the cylinders A and B' are connected by a by-pass 28, shown in dotted lines Fig. 3 and in plan Fig. 6, and by this arrangement the final discharge 40 of air from the cylinder B' will pass to cylinder A and thence flow through a passage 29 to the outer end of cylinder 30 and in like manner the air will flow from cylinder B to A' and thence through the passage 29 to the 45 symmetrically arranged cylinder 30 at the other end of the motor. The air pressure created by the pistons after passing the exhaust ports 26 will thus become effective in each cylinder 30 upon a piston 31 therein 50 which is connected by stem 32 to a piston valve 33 disposed in each chamber 34 and working therein as a cylinder so as to pass to one side or the other of the exhaust ports 26 which open into such cylinder. With 55 the pistons 18 in compressed position, the pistons 31 stand at the outer ends of their respective cylinders 30, leaving the ports 26 in direct communication with the chambers 34. As the pistons move outwardly the air 60 behind them is forced through these ports 26 and compressed in the chambers 34 until the pistons pass the ports 26, whereupon the air is forced through the passageways 28 and 29 and the pressure rises in the cylinders 30 dis- 65 placing the pistons 31 and shifting the valves 33 so as to bring the ports 26 into communication with the atmospheric exhaust ports 35 in the cylinders 30 and at the same time the pistons close the ports 27 and the exhaust of the burnt gases takes place through ports 26, 70 cylinders 30 and exhaust ports 35, which ports extend substantially around the cylinders 30, see Fig. 4. This inward movement of the valve 33 will operate a plunger 36 in each injector and will spray oil into the combustion chamber 19. As soon as the exhaust of gases takes place the pressure in the chamber 19 is relieved and the compressed air in the chambers 34 will open air valves 37 which are held normally closed by the action 75 of spring 38. Each chamber 34 is provided with an inwardly opening automatic intake air valve 39 (see Fig. 4) having a valve stem 40 urged by a spring 41 to closed position and which is adapted to be sucked 80 open by the inward stroke of the pistons which suction is effective through ports 26 to chambers 34 after the piston valves 33 have moved to their outer position in response to both suction and centrifugal force. 85 It is to be noted that as the piston valves 33 are moved inwardly by pistons 31 they will further compress the already compressed air in the chambers 34 and this air pressure will bring the pistons to rest about three-fourths 90 of their full inward stroke. This partial movement is not effective to move the oil feed plungers 36, due to the fact that a spring 42 is interposed between each stem 43 on the piston 33 which telescopes in the 95 plunger 36 so as to absorb this partial movement, but as soon as the exhaust of gases has dropped the pressure in the chamber 19 low 100 enough for the valves 37 to open, the pressure in chambers 34 will drop to atmosphere 105 and the piston valves are then free to complete their stroke, in doing which the stems 43 will engage the plungers 36 and move them to spray a charge of oil along with the air entering past valves 37 into the combustion chamber. Before this occurs, however, 110 it is important to note that an ample volume of air will have previously passed valves 37 and scavenged the combustion chamber 19 to the cylinders. 115

It will be noted, especially by reference to Fig. 3, that the piston valves 33 are each provided with a curved rearwardly inclined deflector 44 integral with their outer surface and so disposed as to catch and direct the 120 exhaust gases, entering the cylinders 30 through the ports 26, and divert them so that they will be discharged at considerable velocity through the exhaust ports in a rearward direction so as to assist in propelling the rotating motor. It will also be noted that when the valve 33 is moved to its inward or atmospheric exhaust position, this deflector 44 will drop below the exhaust port 125 35 and will therefore not interfere with the 130

rush of air induced by the motion of the rotor through the substantially circular exhaust port 35, but will cause the exhaust gases to be diverted in the direction of the flow of the air so as not only not to retard the latter but to appreciably augment it. This through draft of air materially assists by a suction effect in the scavenging of the cylinders. The webs 45, which interrupt the exhaust port, are more clearly shown in Fig. 4, and in each of these I provide a longitudinal slot 46 in which a guide tongue 47 on an extension 48 of the piston 31 works and prevents the piston valve 33 turning the plunger stem 43 out of alignment with the injector.

Each piston rod 17 at its outer end is connected to a yoke shaped cross arm 49 which at its outer ends is turned to form bearings 20 for the rollers 50 or 51. The cross arms on the piston rods for the cylinders A and A' are shorter than the cross arms for the pistons in cylinders B and B' and the rollers on the short arms are designated 50 and on the long arms 51. It will be seen that the diametrically opposite cross arms are alike and this keeps the rotor in balance. The rollers 51 will travel on the inner tracks adjacent to the side walls 2 of the stator casing and the rollers 50 will travel on the inside or spaced tracks. In other words, the tracks for the rollers 51 are composed of the cam sections 4, 5 and the intervening portions of the casing rim, representing concentric track sections 6'. The several rollers are mounted on anti-friction roller bearings 52 and they travel between the cam tracks as an outer bearing and fixed guide tracks 53 as an inner bearing. This cam track opposite the track sections marked 54 is provided with a concave section 55, on which the rollers 51 travel, while it is provided with a continuous symmetrical convex section 56 on which the rollers 50 travel. The concave section 55 is necessary for the wheels 51 to pass the point 54 on the outer cam, but this is not needed for the wheels 50 as the latter will travel on the cam track 5 at this point, but if for any reason the pistons connected to the rollers 50 should not move outwardly following the cam track, this convex portion will ride them past the concave 55 and thus prevent them dropping thereto and locking the motor. The cylinder heads carry winglike extensions 57 which are partly supported by the side walls of the cylinders 30 and are provided with flat parallel guide faces 58 along which shoes 59 on the cross arms travel. These slides in reality constitute thrust blocks which transmit the lateral thrust from the cam tracks to the motor as the rollers are driven thereby and they also serve to take the lateral strain off piston rods and prevent the cross arms and pistons from turning.

The lubricating system consists in an oil inlet port provided by the central bore 60 in an axle 8 through which the fuel oil pipe passes. The lubricating oil entering the bore 60 is diverted through passages 61 in the spider 10 (see Fig. 4), and enters the chambers 34 and it passes thence to the outer end of said chambers in response to centrifugal pressure and its inertia and enters the inner end of the cylinder 30 through a port 62 and thence passes through the exhaust ports 26 in the outer ends of the motor cylinders and thence passes through the passages 29 to the outer end of the cylinders 30, thus lubricating the pistons 31. Also spring pressed ball check valves 63 will admit the oil under predetermined pressure to enter ducts 64, each of which at its opposite ends enters the stuffing boxes 16 for the adjacent piston rods. These stuffing boxes are provided with an annular oil ring or groove and the piston rods at their inner ends are provided with lubricating passages 65 leading therethrough and radially through their pistons to an oil ring groove 66 surrounding each piston. These passages at the outer ends of the piston strokes will register with the oil grooves 67 in the stuffing boxes 16 and thus a supply of oil under pressure will be forced to the piston rings. Should there be a tendency for either diagonally opposite pair of cylinders to take too much oil, the ports 65 for the pistons of such cylinders can be set slightly further from the pistons, thus causing them to pass beyond the oil grooves 67 in the stuffing boxes to a greater or less extent and thus to modify the interval of register and the volume of oil fed. Bumpers 68 are provided at the outer ends of the cylinders 30 for the pistons 31 to rest on.

The operation of my invention will be better understood by reference to the diagrammatic views shown in Figs. 8 to 12 where the cylinders are appropriately designated and shown in their principal operating positions. Starting with the pistons at firing point the rollers are all in position ready to ride down their respective cam tracks 5 and 7, and it will be noted that the valves 37 are closed and the valves 33 are in position to throw the cylinders in communication with the chambers 34. As the explosion takes place the rollers are thrust down the cam tracks 5 and 7 at their point of maximum inclination and in doing so the motor is shifted to the position shown in Fig. 9 and then in Fig. 10 which complete its power stroke. In the position, Fig. 9, the motor pistons have closed the exhaust ports into the chambers 34 and are beginning to compress air against the valve pistons. At the completion of the power stroke, Fig. 10, the compressed air from each pair of cylinders has acted to shift the adjacent piston 31 its full stroke, thereby opening

the exhaust from the cylinders to the atmosphere and forcing first the compressed air and then the oil spray into the combustion chamber. In the short cycle of movement 5 between the positions in Figs. 10 and 11, it will be observed that the cam track 4 will shift the pistons in the cylinders B, B' inwardly in advance of the pistons in the cylinders A, A', thereby scavenging the cylinders and forcing out the burnt gases. The pistons in the cylinders A and A' are shifted quickly enough to close the exhaust ports before the escape of the mixture and the motor is then ready to assume the final position 15 of its cycle shown in Fig. 12, in which all pistons are being forced inwardly to full compression positions shown in Fig. 8.

It will be understood that my invention may be modified in various particulars without departing from the novel principles of construction and design which form the essence of my invention and I therefore do not desire to be limited to the detail structure shown. For instance, fluid pressure may be 25 used to drive the motor instead of the explosive mixture.

Having thus described my invention, what I claim as new and desire to secure by Letters Patent, is:—

30 1. In a rotating cylinder engine, a stator having cam tracks, a rotor having a pair of parallel cylinders communicating at their middle across the rotor center, two oppositely moving pistons in each cylinder, rollers on the pistons adapted to co-act with said cam tracks substantially as described, and means to supply motive fluid to and exhaust it from said cylinders.

40 2. In a rotating cylinder engine, a stator having cam tracks, a rotor having cylinders offset from its center and provided each with a pair of opposing pistons, rollers on the pistons to co-act with said cam tracks, and means to supply motive fluid to and exhaust it from said cylinders, said cam having zones of maximum inclination opposite the piston rollers as they start their power stroke.

50 3. In a rotating cylinder engine, a stator having cam tracks, a rotor having cylinders offset from its center and provided each with a pair of opposing pistons, rollers on the pistons to co-act with said cam tracks, means to supply motive fluid to and exhaust it from said cylinders, said cam tracks having zones of maximum inclination opposite the piston rollers as they start their power stroke, and slide bearings on the rotor to take the side thrust strain on the rollers.

60 4. In a rotating cylinder engine, a plurality of offset parallel cylinders communicating near their centers, a pair of oppositely moving pistons in each cylinder, rollers on the outer ends of the pistons, and a substantially elliptical track co-acting with the

rollers and having zones of maximum inclination disposed to engage the rollers during their maximum power stroke.

5. A rotating cylinder engine as defined in claim 1 having the power zones of the 70 tracks inclined in the direction of the piston thrust, such inclination being maximum at the beginning of the stroke and formed by abrupt outwardly sloping surfaces which return by gradual curves to the track of the 75 rollers in full extended position.

6. A rotary cylinder engine comprising a rotor having a cylinder provided with a pair of opposing pistons and rollers on the pistons, and a stator comprising a cam track 80 having concentric and eccentric curves disposed to be simultaneously engaged by said piston rollers during the exhaust scavenging intake and compression operation.

7. A rotary cylinder engine comprising a 85 rotor having a cylinder offset from the rotor center and provided with a pair of opposing pistons and rollers on the pistons, and a stator comprising a cam track having concentric and eccentric curves disposed to be simultaneously engaged by said piston rollers.

8. In a rotary cylinder engine, a stator comprising a symmetrically curved cam track 95 comprising eccentric and concentric curved portions, and a rotor comprising two offset cylinders, each having a pair of opposed pistons, said cam track being arranged to cause diametrically opposite pistons of different 100 cylinders to co-act with similar opposed portions of the cam.

9. A rotary engine comprising a stator having cam surfaces and a plurality of offset cylinders therein, a common equalizing chamber having air and gas intakes and 105 sparking means, the pistons for the cylinders having rollers co-acting with said cam surfaces, the cylinders being closed at their outer ends, and exhaust means for the cylinders automatically controlled by the air 110 compression in the outer ends of the cylinders.

10. A rotary engine according to claim 9, in which the outer ends of adjacent cylinders are connected, and a common exhaust valve 115 is provided for each connected pair of cylinder ends and controlled by the joint air pressure created therein.

11. An internal combustion rotary engine according to claim 1, in which the cam tracks are symmetrical and comprise each opposing pairs of adjacent differently curved surfaces adapted respectively to be simultaneously engaged by the rollers of adjacent pistons as they complete their power strokes, and the like cam surfaces engaged by one pair of diametrically opposite pistons being concentric with the rotor while the cam surfaces engaged by the other pair of pistons being eccentric to the rotor and adapt- 120 125 130

ed to allow said latter pistons to complete a return scavenging stroke before the other pistons close the exhaust.

12. In a rotary internal combustion engine, a stator comprising cam ways, a rotor comprising a plurality of cylinders having pistons, rollers at the outer ends of said pistons engaging said cam ways, exhaust ports for the cylinder, chambers into which 10 said exhaust ports open and which have an atmospheric exhaust port, an automatic piston valve controlled by the centrifugal force and air pressure at the outer end of its respective motor cylinder and movable thereby into one position to bring said exhaust ports into communication, an automatic internally opening air admission valve for each chamber, an outwardly opening air exhaust valve leading from each chamber into the 15 explosive end of its respective cylinder, and means to supply fuel to and to ignite it in the cylinders.

13. An internal combustion rotary engine comprising a stator having cam tracks, a 20 rotor comprising parallel offset cylinders closed at their outer ends and communicating at their middle portions, reciprocable pistons in the ends of said cylinders, rollers on the outer ends of the pistons and adapted 25 to engage said cam tracks, and automatic means to scavenge and recharge the cylinders, substantially as described.

14. A rotary internal combustion engine comprising a stator, a rotor provided with 30 offset cylinders having pistons with rollers on the exposed ends of the pistons, means to close the outer ends of the cylinders, and an exhaust port for the cylinders having a 35 free draft opening therethrough parallel 40 with the plane of rotation of the rotor.

15. A rotary internal combustion engine according to claim 14, in which a common 45 exhaust valve is provided for the adjacent ends of cylinders on the same side of the rotor and is designed with a deflecting surface disposed to direct the exhaust gases in the direction of flow of air through its respective exhaust port.

16. A rotary motor as described in claim 50 1, in which the cam tracks comprise concentric curved portions adapted to hold through a predetermined angular travel part of the pistons engaging them at the extreme inner and part at the extreme outer ends of 55 their stroke.

17. A rotary internal combustion engine comprising a stator having cam ways, a rotor having cylinders arranged in opposite pairs closed at their outer ends, pistons in 60 the cylinders having the piston rods projecting through the closed outer ends of the cylinders, rollers on said piston rods coacting with the stator cam ways; a chamber between each pair of cylinders having a 65 cylinder at its outer end, an intermediate

exhaust port and a piston valve chamber near its inner end; a piston movable in said latter cylinder, and an exhaust valve connected to said latter piston, exhaust ports leading from near the outer ends of adjoining motor cylinders into the adjacent valve chamber, ports leading from the outer ends of the adjacent chambers to the outer end of the valve piston chamber, an automatic suction operated intake air valve for said 70 chamber, a pressure controlled outlet valve opening from said chamber into the inner ends of its adjacent motor cylinders, and means controlled by the movement of the exhaust valve to admit fuel to its respective 75 motor cylinders, substantially as described.

18. A rotating internal combustion engine comprising a stator having cam ways and cam surfaces, a rotor having cylinders closed at their outer ends, pistons therein 80 and rollers connected to the pistons and co-acting with said cam surfaces, means to introduce oil into the rotor and conduct it to the outer ends of the cylinders to lubricate 85 said pistons, and pressure controlled means 90 to feed the oil from the outer ends of the cylinders to the working surfaces of the pistons, substantially as described.

19. In a rotary cylinder engine, a stator having cam tracks, a rotor having parallel 95 offset cylinders closed at their outer ends and connected at their centers across the rotor center, pistons in the cylinders, and bearings on the pistons which co-act with the stator cam tracks, substantially as described. 100

20. A rotary cylinder engine as described in claim 13, in which the air, gas and sparking elements enter a chamber connecting the middle portion of the cylinders.

21. A rotary cylinder engine comprising 105 a stator having a double cam track, one track comprising opposed portions which project substantially beyond the adjacent portion of the other track, a rotor comprising offset cylinders having opposing pistons, 110 and rollers on said pistons, the adjacent rollers being disposed to follow different tracks throughout the rotation of the rotor, substantially as described.

22. A rotary cylinder engine as de- 115 scribed in claim 21, in which the two tracks comprise similar sharply inclined curved portions disposed to stand opposite all the pistons at the moment of their power stroke.

23. A rotary cylinder engine as described 120 in claim 21, in which the tracks have portions lying in the same curved planes connecting their relatively offset portions.

24. A rotary cylinder engine as described 125 in claim 21, in which the track following the minor axis is provided with opposed curved zones concentric with the rotor axis and disposed to hold the pistons while traversing it in extreme inward position.

25. In a motor, a stator having cam tracks, 130

a rotor having two parallel cylinders closed at their outer ends and offset on each side of the motor axis, two opposed pistons in each cylinder with piston rods reciprocating through the closed ends of the cylinders, each diametrically opposite pair of pistons engaging through suitable bearings, a separate track, each track forming a system of curved cams arranged to control the opposed 5 pistons in each cylinder and comprising four similarly and sharply curved zones disposed opposite the pistons during their power strokes.

26. A rotating cylinder engine as defined 15 in claim 4, in which means are provided to form an air cushion to take the momentum and centrifugal force of the pistons on their outward stroke to utilize the same to co-operate with the track in starting the pistons 20 on their inward stroke.

27. A rotary cylinder engine according to 25 claim 1, in which the cross heads of co-acting pistons are of different lengths and in which cam tracks of different curvilinear conformation are provided for the rollers on said different cross heads, the sections of the track for the rollers on the longer cross heads being spaced to allow the shorter cross heads and the rollers thereon to pass between said sections.

28. A rotary cylinder engine as described 35 in claim 1, in which two separate mixing chambers are provided between the said pair of cylinders comprising pressure controlled automatic valves regulating the admission of air and gas to said chambers, the discharge 40 of the mixture therefrom into the cylinders, and the exhaust of gases from the cylinders through said chambers.

46. 29. A rotary engine as described in claim 1, in which the pistons are mounted on piston rods having inwardly curved cross heads on their outer ends on which cross heads rollers are mounted, and in which the outer ends 45 of the cylinders are closed and provided with stuffing boxes for the piston rods.

50. 30. In a rotary cylinder engine, a rotor comprising an offset cylinder having its outer ends closed, opposing pistons operable in said cylinder, automatic pressure controlled mechanisms on each side of the axis of the engine and controlling a common feed of gas to the center of the cylinder, and an independent exhaust of gases from the ends 55 of the cylinder.

31. A rotary cylinder engine as described

in claim 1, in which the supply and exhaust means are symmetrically arranged at both ends of the cylinders.

32. A rotary cylinder engine as described 60 in claim 1, in which two gas supply and exhaust means comprise independent automatic elements which are symmetrically disposed on each side of the axis of the engine between the said cylinders.

33. A rotary cylinder engine as described 65 in claim 30, in which each of said mechanisms comprises a chamber having gas intake ports at its inner end and gas exhausts ports at its outer end, and cylinder exhaust 70 ports entering an intermediate zone, there being an automatic pressure controlled valve movable in the chamber to both modify the pressure on the mixture therein and to control the communication between the several 75 exhaust ports entering it.

34. A rotary cylinder engine as described 80 in claim 30, in which each of said mechanisms comprises a chamber having gas intake ports at its inner end and gas exhaust 85 ports at its outer end, and cylinder exhaust ports entering an intermediate zone, there being an automatic pressure controlled valve movable in the chamber to both modify the pressure on the mixture therein and to control the communication between the several 90 exhaust ports entering it, in which said floating valve is operated by a piston exposed to the pressure trapped at the extreme outer 95 end of the engine cylinder and moved thereby to increase the pressure on the mixture at the inner end of said chamber.

35. In a rotary cylinder engine, a rotor comprising a cylinder having opposing pistons therein, a stator having cam tracks with 95 which the outer ends of the pistons co-act, axes on the rotor journaled in the stator and connected by webs to the outer cooler ends of the cylinder.

36. In a rotary cylinder engine, a rotor 100 comprising a cylinder having opposing pistons therein, a stator having cam tracks with which the outer ends of the pistons co-act, axes on the rotor journaled in the stator and connected by webs to the outer cooler ends 105 of the cylinder in which a ventilating space is left between the intermediate portion of the webs and the middle or hotter portion of the cylinders.

In testimony whereof I affix my signature.

GEORGE EDGAR BRAGG.
